UNITED STATES PATENT OFFICE

ROBERT T. MORRISON, JR., OF MEDINA, OHIO.

CAR-COUPING.

SPECIFICATION forming part of Letters Patent No. 323,195, dated July 28, 1885.

Application filed December 10, 1884. (No model.)

To all whom it may concern:

Be it known that I, ROBERT T. MORRISON, Jr., of Medina, in the county of Medina and State of Ohio, have invented certain new and 5 useful Improvements in Car-Couplers; and I do hereby declare the following to be a full, clear, and exact description of the invention, such as will enable others skilled in the art to which it pertains to make and use the same.

10 My invention relates to improvements in car-couplers, having for its object a combined automatic hook-coupler and substantially an ordinary link-coupler.

With these objects in view my invention 15 consists in certain features of construction, and in combination of parts, hereinafter described, and pointed out in the claims.

In the accompanying drawings, Figure 1 is a plan view showing two of my improved devices coupled by their respective hooks. Fig. 2 is a plan view of one of my improved draw-heads coupled by a link to an ordinary draw-head. Fig. 3 is an end view in elevation of my improved draw-head and hook-coupler. 25 Fig. 4 is a view in perspective of the hook.

A represents the draw-head proper, that is attached to any draw-bar of ordinary construction, A'. On the respective sides of the draw-head, and integral therewith, are the bumpers 30 B and B', of unequal length, and adapted to receive the thrust of similar bumpers on an opposing draw-head. These bumpers are separated far enough to admit an ordinary link-fastening draw-head between them, and the 35 part A has a flat face, a, and a link pocket and pin, a' and a'', so that these draw-heads may be coupled in the usual manner with the ordinary link-coupling devices.

C is the hook-coupler, that extends back 40 into the slot D, and is pivoted on the pin d, the pin crossing the plane of the hook at a right angle, and each standing at an angle of about forty-five degrees from a transverse horizontal line through the draw-heads; consequently opposing hooks stand or move at 45 right angles to each other. The hooks, as shown in Fig. 4, have an inclined under face, c, at the forward end, by means of which, when the opposing hooks are brought together, one 50 or both of the hooks are raised obliquely until the points have passed each other, and then fall by gravity and engage a hook over each

other, as shown in Fig. 1. In case a link-coupling draw-head approaches, the hook, by means of the incline aforesaid, mounts, unless 55 otherwise elevated, the draw-head, and remains resting upon it. When the draw-heads are not coupled the bottom wall of the slot D is about in the position shown in Fig. 3, and ready to engage another hook on a link-coupling draw-head. The face of the hook proper c' is slightly curved, as shown, and recedes from the pivotal point as it approaches the shank, and, by means of such form, two hooks, when engaged, have a tendency to draw 60 together rather than to separate. The one side of the face a is cut away at a', to make room for the point of the opposing hook; but there is still left ample surface to form a bumper, so that this part of the device is substantially as an ordinary link-coupler. 65

The hooks may have a chain, cord, rod, or any suitable device connected at c', by means of which the hooks may be uncoupled from the side or top of the cars, and by means of 70 such attachment the hook may be in any suitable manner held with its free end suspended in the position shown in Fig. 2.

The face of the hook c' is of such length that several inches difference in the height of cars 75 will not interfere with the operation of the hooks that in such cases will engage each other, the one near the point and the other near the shank of the hook.

The bumpers B and B' might be of equal 80 length, each extending about half as far as the former; but in such cases it would not be so convenient to couple with links as with the construction shown, where one side of the draw-head is unobstructed. 85

The pocket a', the slot D, and the pin-holes may all be formed so that little or no fitting is required, and the device can therefore be made at a small initial cost, while the absence of springs and complicated mechanism is greatly 90 in its favor as a durable and practicable car-coupler. 95

What I claim is—

1. The combination, with a draw-head having an elongated open slot formed therein, 100 preferably at or about an angle of forty-five degrees from a transverse horizontal line through the draw-head, of a hook pivoted at one end within said slot and extending outward and

terminating beyond or outside of the draw-head, substantially as set forth.

2. The combination, with a draw-head having an elongated open slot formed therein, 5 preferably at or about an angle of forty-five degrees from a transverse horizontal line through the draw-head, and also provided with a buffer-face and link-pocket, of a hook pivoted at one end within said slot, and extending out-
10 ward and terminating beyond or outside of the draw-head, substantially as set forth.

3. In car-couplers, the combination, with a

draw-head with link-pocket, pin, and buffer, and a hook pivoted so as to swing outward and upward and return by gravity, of buffers of 15 unequal length on either side of the link-buffer, substantially as set forth.

In testimony whereof I sign this specification, in the presence of two witnesses, this 24th day of November, 1884.

ROBERT T. MORRISON, JR.
